HASP TYPE CASE LATCH

Eugen Doquier, Iserlohn, Germany, assignor to
 Heinrich Hulter, Jr., Iserlohn, Westphalia, Germany, a firm of Germany

Application March 12, 1952, Serial No. 276,109
 In Germany March 29, 1951

7 Claims. (Cl. 292—165)

1

The present invention relates to an improved lock for cases, in which latter term is included suitcases, travelling cases, brief cases, attaché cases, hold-alls, trunks, satchels, portfolios, portmanteaux, and like articles. Moreover, the invention relates to a lock of this character which includes a hasp, a latch bolt for engaging this hasp, and a pressing member for actuating the latch bolt (and hereinafter referred to as a "thumb piece"), which member is disposed at the front side of the lock.

It is desirable to secure, in such locks, a construction of small depth so that the body of the lock will lie flat on the surface of the case whereby, when the case is shut and in use, striking of the lock and consequent damage thereto, and even the unintentional unfastening of the latch which may sometimes occur, is as far as possible precluded.

It has therefore been proposed to make the thumb piece pivotable and to mount it in the front wall of the lock casing. In this instance the pivoting movement of the thumb piece is transmitted to a tongue-like, cooperating, double-armed rocking lever pair through oblique surfaces provided on arms opposed to a closure nose on this rocking lever pair. With this arrangement it is necessary to lock the pivotal movement of the thumb piece by means of a tumbler to permit the closure of the lock, and to this end the thumb piece is provided with a keyhole beneath which is arranged a disc-form tumbler. The degree of movement of the thumb piece necessitates a fairly extensive forward movement of the free edge of this thumb piece, so that the front wall of the locking casing has to be of gable-end sectional shape to enable it to enclose the thumb piece on all sides.

It is, therefore, one object of the present invention to provide a simpler lock construction, which comprises a casing, a thumb piece which is arranged for pivotal movement about an axis in or on the casing, and offset from the face of this piece, and a latch bolt adapted to be projected into and withdrawn from, a hasp or a part on the latter, and in which the latch bolt is of flat section, is mounted for longitudinal sliding, and is provided with a part having a surface oblique with respect to the path of travel of this latch bolt and cooperating with a part of the thumb piece remote from said pivotal axis.

It is another object of the present invention to provide the described lock construction in which a single spring can be used to operate both the return movement of the latch bolt and of the thumb piece, and also suitable tumblers may be

2

arranged to provide access to which a keyhole and key guide can be disposed beside the thumb piece, thus facilitating the closure of the lock.

It is still another object of the present invention to provide a lock structure in which the latch bolt is fixed when locking takes place, thereby rendering the lock reliable and safe.

It is yet another object of the present invention to provide a lock structure in which conveniently the latch bolt has a tail at its outer end carries an oblique surface part, and the corresponding outer end part of the thumb piece is adapted to ride over such oblique surface when this piece is depressed, and thereby pivoted, so as to cause sliding of the latch bolt and withdrawal of the same from the hasp.

It is a further object of the present invention to provide a lock structure in which the oblique surface may suitably be provided by a tongue stamped out or likewise formed from the latch bolt body and bent back, to enable the latch bolt to be made inexpensively from a single piece of sheet metal.

It is still a further object of the present invention to provide a lock structure in which the lock can be equipped with a readily applied enclosing cover plate provided with openings for accommodation of the outstanding parts of the structure, e. g. the hasp and the thumb piece, whereby the front of the lock is given a flush surface, in view of the flat and smooth lock construction.

It is also an object of the present invention to provide a lock structure in which such a cover may be of thin sheet metal and of box shape and be dimensioned to fit the lock casing snugly, being simply pushed thereover and having its side walls engaging those of the casing with a forced fit, and in which in addition the front wall of this cover may have an opening providing a keyway, this keyway opening being defined by a collar cooperating with the front plate of the lock casing to serve as a supporting and centering means, thereby determining the required distance which the front wall of the cover stands outwardly of the lock casing, i. e. the required distance to provide the "flush" effect, by the collar.

It is, yet, a further object of the present invention to provide a lock structure in which, in order to save material, the cover may be dispensed with, and the lock casing has its front wall or plate, in the locked condition, flush and substantially so with the front surface of the thumb piece, and this wall or plate has an indentation for accommodation of the hasp.

With these and other objects in view, which will become apparent in the following detailed

description, the present invention will be clearly understood in connection with the accompanying drawings, in which:

Figure 1 is an elevational view of the lock with the hasp pressed down;

Fig. 2 is a section along the lines 2-2 of Fig. 1;

Fig. 3 is a section along the lines 3-3 of Fig. 1;

Fig. 4 is a section along the lines 4-4 of Fig. 1;

Fig. 5 is an elevational view of the internal structure of the lock;

Fig. 6 is a longitudinal section through the same, taken along the lines 6-6 of Fig. 5; and

Fig. 7 is a cross-section along the lines 7-7 of Fig. 5.

The casing of the lock is formed by a front plate 1 and side walls 2, this front plate being furnished with a slot 3 for the entry of a loop 5 on the hasp 4 of the lock. In addition, the plate 1 of the lock casing has an opening 6 which is filled by a thumb piece 7. Furthermore a key 15 guide is also preferably arranged in the plate, this conveniently taking the illustrated form of a rotatable cap 10 having a key hole 9.

The hasp 4 has a spring hinge 11 so that, on release, it will swing up automatically from the closure position, relatively to a mounting flange 12.

The latch bolt 13 of the lock, which is adapted to engage in the loop 5 of the hasp 4 to secure the closure, is moved by actuating the thumb piece 7. As is illustrated by Fig. 5, this piece 7 is arranged to pivot on a hinge pin 14 mounted in a housing 15 which covers the internal lock elements from the exterior at the otherwise open side of the lock casing.

The latch bolt 13 is arranged to slide on the bottom of housing 15 under the action of a spring 16, preferably a torsion spring, which has arms bearing respectively against the locking latch bolt 13 and a fixed part, for example the hinge pin 14, as illustrated.

This latch bolt 13 has an opening 17 accommodating a guide lug 18 and also registering with the keyhole 19.

At its outer end the latch bolt 13 has a tail which is furnished with an inclined surface formed by bending up a tongue 20, this being disposed behind a freely-pivoting inturned flange 21 on the thumb piece 7. Thus, when this piece 7 is pressed in, the flange 21 slides over the inclined surface 20 and withdraws the latch bolt 13 from its locking position, against the opposition of spring 16, whereby the nose 22 of the latch bolt 13 releases the loop 5 on hasp 4.

As will be observed from Figs. 1 to 4, the lock casing is enclosed by a box-like cover having a front wall 24 and adjoining side walls 25. These side walls are a tight fit on the walls 2 of the lock casing so as to secure the cover firmly to the lock casing when it is pushed into position over it.

The front wall 24 of the cover is provided with an opening 27 corresponding in outline shape to that of the hasp 4. In addition this front wall 24 of the cover has an opening 28 for the thumb piece 7, and is arranged at a distance from the front plate 1 so as to lie flush with the parts outstanding from this plate, i. e. the hasp 4 and thumb piece 7. In this connection it is to be noted that the thumb piece 7 is preferably so cranked from its mounting around hinge pin 14 that the surface thereof lies parallel with that of the front wall 24 of the cover.

The key guide 10 is in register with a further opening 26 having its defining rim turned back

relatively to the wall 1 to form a sort of collar. When the cover is slipped into position over the lock casing this collar, which is disposed more or less in the center of the face of the cover, abuts against the front surface of plate 1 so as to support and center the cover, whereby variations in the spacing will not occur in use, even as a result of knocks or pressure stresses.

Instead of using a cover as described, the lock casing 1 can be so constructed that its front outer face is uniplanar or flush with the surface of the thumb piece 7 and an indentation corresponding to the outline shape of hasp 4 is pressed into plate 1, so that the hasp will lie snugly therein.

While I have disclosed two embodiments of the present invention, it is to be understood that the embodiments are given by example only and not in a limiting sense, the scope of the present invention being determined by the objects and the claims.

I claim:

1. A case lock comprising a casing having an opening, a thumb piece disposed in the said opening of the casing and pivotally mounted in the latter upon an axis parallel to and offset from the front face of the said thumb piece, the said casing having a slot adapted to receive a loop member of a hasp when in locked position, and a latch bolt adapted to be projected into and withdrawn from the hasp loop, the said latch bolt being of flat cross-section and mounted for longitudinal sliding in the said casing, the said latch bolt including a part having a surface oblique with respect to the path of travel of the latch bolt and cooperating with a part of the said thumb piece remote from the said pivotal axis, so that upon pressing upon the said thumb piece, the said latch bolt is withdrawn.

2. The case lock, as set forth in claim 1, in which the said part of the latch bolt having an oblique surface comprises a tail disposed at its outer end, and in which the corresponding outer end part of the thumb piece is adapted to ride over the oblique surface when the thumb piece is depressed, and thereby pivoted, so as to cause sliding of the said latch bolt and withdrawal of the same from the hasp loop.

3. The case lock, as set forth in claim 1, in which the said part of the latch bolt having an oblique surface comprises a tongue stamped out from the said latch bolt and bent back to a pre-determined angle relative to the plane of the said latch bolt.

4. The case lock, as set forth in claim 1, which includes a cover for the said lock, the said cover having an opening and a slot, respectively, corresponding to the opening and slot of the said casing receiving said thumb piece and adapted to receive a loop member, respectively, and the said cover being mounted over the lock casing in such manner that its front face lies substantially flush with the forwardly outstanding thumb piece of the lock.

5. The case lock, as set forth in claim 4, in which the front wall of the said cover has an opening, the latter being defined by a collar cooperating with the front plate of the said casing to serve as a supporting and centering means.

6. The case lock, as set forth in claim 4, in which the said cover has side walls engaging the corresponding side walls of the said casing with a forced fit.

7. The case lock, as set forth in claim 1, in which the front wall of the said casing is, in the locked condition, substantially flush with the

front surface of the said thumb piece, and in which the front wall of the said casing has an indentation adapted to accommodate the hasp.

EUGEN DOQUIER.
